UNITED STATES PATENT OFFICE.

WILLIAM H. KIRNAN, OF BAYONNE, NEW JERSEY, ASSIGNOR TO THE GAME-WELL FIRE-ALARM TELEGRAPH COMPANY, OF NEW YORK, N. Y.

POLICE-SIGNALING APPARATUS.

SPECIFICATION forming part of Letters Patent No. 537,161, dated April 9, 1895.

Application filed December 28, 1892. Serial No. 456,557. (No model.)

To all whom it may concern:

Be it known that I, WILLIAM H. KIRNAN, a citizen of the United States, residing at Bayonne, county of Hudson, and State of New Jersey, have invented a certain new and useful Improvement in Police-Signaling Apparatus, (Case F,) of which the following is a specification.

The object I have in view is to provide means for the ringing of the emergency bell in police signaling apparatus, which will be reliable in operation and will not be dependent for its working upon changes in the character of the current impulses transmitted, *i. e.*, changes in current strength, current polarity, or time duration of signal impulses, nor require the employment of a separate bell circuit.

In carrying out my invention, I provide at the receiving station a bell circuit-controller, which works by a step-by-step movement and must be advanced a certain number of steps before it operates to close the bell circuit controlled by it. This circuit-controller is operated by an electro-magnet through a pawl and ratchet, which electro-magnet is controlled by the main line relay and advances the circuit-controller one step each time the armature of the main line relay falls back and closes the local circuit through it. A train of wheels is started by the first movement of this circuit-controller and carries a cam, which, after a certain extent of movement of the train, opens the local circuit through the magnet which operates the bell circuit-controller, making such magnet unresponsive to subsequent movements of the relay armature, which relation of the parts is maintained until the completion of the signal. The continued movement of the train trips a pawl, holding the circuit-controller in its advanced position, and allows such circuit-controller to be drawn back by a spring to its normal or initial position. If, before the cam moved by the train of wheels opens the circuit of the magnet which works the circuit-controller, a sufficient number of breaks have been made in the main circuit to cause this magnet to advance the circuit-controller far enough to close the bell circuit, then the bell will be sounded; but if the impulses received during this interval are not

sufficient in number to produce this result, then the circuit-controller is tripped and returns to its initial position without closing the bell circuit.

55

As a specific illustration, if the signal-boxes are arranged to send in one or more of six dots or dashes constituting special service signals, followed by other dots or dashes representing the box number, and if it is desired that the emergency bell shall remain silent if only three special signal impulses are transmitted, and shall ring if four, five or six special signal impulses are transmitted, then the bell circuit-controller will be arranged to close the bell circuit when such circuit-controller has been advanced four steps. The cam which opens the local circuit in which the magnet operating the circuit controller is located, acts to open such local circuit only while the impulses representing the box number are being received. Such box number impulses are, therefore, incapable of acting on the bell circuit-controller, and the magnet working that circuit-controller responds only to the impulses forming the special service signals. If only one, two or three of such special signal impulses are sent over the line, the circuit-controller will not be advanced far enough to close the bell circuit, but if four or more of such special signal impulses are transmitted, the bell circuit-controller will close the bell circuit on the fourth impulse, and the bell will then ring continuously until stopped. Thus it will be seen that the operation of the emergency bell is made dependent upon the transmission of more than a certain number of special signal impulses, and is independent of the character of the impulses, since any impulse, whether a dot or a dash, which will work the main line relay, will also work the local circuit in which the bell circuit-controller magnet is located. The details of this and other features of the apparatus are illustrated by the accompanying drawing, which shows, partly in diagram, an arrangement of apparatus and circuits embodying the invention.

The signal-box, in connection with which the invention is illustrated, is provided with two circuit-breaking disks A, B, revolved together by a spring-operated train as usual, and making one complete revolution each

time the box is operated. The circuit wheel A is provided with notches *a*, which produce the box number, in this case No. 23. The wheel A also has a notch *b*, which, together with five other notches *b'*, *b²*, *b³*, *b⁴*, *b⁵*, upon the wheel B, produce the special service signals. A circuit-breaking spring A' bears upon the wheel A, and a similar spring B' bears upon the wheel B. These springs are connected with wires 4, 5, forming opposite sides of the main circuit. The spring B' and wheel B are shunted by wires 6, 7, extending to springs *c*, *c'*, which are normally in contact with each other and carry the current around the notches on the wheel B, so that such notches are ineffective unless the springs *c*, *c'* are separated.

C is the special service pointer, which carries a cam C' engaging with the extended end of the spring *c* when the pointer is turned and separating the springs, opening the shunt 6, 7, and permitting the notches on the wheel B to act upon the circuit. A sector *d*, on the same shaft which carries the wheels A, B, engages with a sector *d'* on the shaft of the pointer C, and turns that pointer back to the position shown in the drawing from any position to which the pointer may be set.

As shown, the box is adapted to send in any one of six special service signals, together with the number of the box. In the position of the pointer shown, if the box is pulled, the shunt 6, 7 remains closed and the spring A' alone is operative. The effect will be to send in the one special signal impulse from the notch *b* on the wheel A, and the box number from the notches *a* on the wheel A. If before pulling the box, the pointer C is adjusted to the second report call, the cam C' will open the shunt 6, 7, making the spring B' operative. The effect of pulling the box then will be to send in special signal impulses from the notches *b* and *b'*, when the sector *d* will strike the sector *d'* and turn the pointer back to its initial position, closing the shunt 6, 7, before the spring B' reaches the notch *b²*. If the pointer is turned to the third report call, the notch *b²* will be brought into operation before the shunt is again closed. For the fourth call, which is the telephone call, notches *b*, *b'*, *b²*, *b³* will be brought into action. For the fifth, or ambulance call, the notch *b⁴* will be added to the preceding notches, while for the sixth or wagon call, all the notches will be brought into action.

With apparatus of this character, it is desirable that an emergency bell should ring at the receiving station with the telephone, ambulance and wagon calls, but not with the report calls. The main circuit 4, 5 extends through the battery M B and the main line relay D, and forms a normally closed circuit. The relay armature D' has two back points, at one of which it closes the local register circuit 8, 9 through the local battery *l b* and the register magnet E. At its other back contact point it closes the local circuit 10, 11,

through the local battery *l b'* and the bell-circuit-controlling magnet F. The armature *e* of the magnet F carries at its upper end a pawl *f*, which engages with the ratchet teeth on the under side of a sliding bar G, which is forced in one direction by the pawl *f* and retracted by the spiral spring *g*.

A spring-locking pawl *h* engages with teeth 75 on the upper side of the bar G and locks it in each position of advancement, preventing it from being retracted until the pawl *h* is tripped. Bearing on the upper side of the bar G is the extended end of a spring *i* which 80 is thereby held out of contact with a second spring *i'*, but when the bar G has advanced far enough to release the extended end of the spring *i*, the springs *i*, *i'* will come together and close a circuit 12, 13, through a 85 local battery *l b²* and the magnet H. The armature lever *k* of the magnet H controls at its front contact point a local circuit 14, 15, through a vibrating bell I, the battery *l b²* being shown as used to supply both the local 90 circuits 12, 13 and 14, 15. When the armature lever *k* is drawn forward by the magnet H, a spring dog *k'* drops back of it and holds it in its forward position, keeping the bell circuit closed until the dog *k'* is moved to release the 95 lever *k*, which may be done by means of a suitable handle *k²* attached directly to the dog *k'* or connected with it by a cord, as shown. The magnet H thus forms a relay for the vibrating bell, but instead of using that 100 magnet to release a drop which closes the bell circuit and keeps it ringing until the drop is re-set, I prefer to use the device described, as a matter of detail, since the device for re-setting it is so simple in construction and so 105 readily operated. The bar G, as shown, is provided with four teeth on each side, and it requires four current impulses to advance that bar the full extent of its movement and permit the springs *i*, *i'*, to close together. K 110 is a spring or weight operated train of wheels, which is held from running by an arm *l* from the pawl *h*, the end of such arm having a tooth engaging a pin on one of the wheels of the train. The train is released when the 115 pawl *h* drops into the first notch of the bar G, this movement throwing the tooth on the arm *l* out of engagement with the pin on the train. The shaft *m* of this train is designed to make one revolution each time the train is started. 120 This shaft carries a cam *n* which acts upon the extended end of a spring *n'*, which is normally in contact with another spring *n²*, such springs *n*, *n²* forming a part of the local circuit 10, 11, including the circuit-controlling 125 magnet F, and acting, when separated, to break the circuit through such magnet. The shaft *m* is also provided with an arm *o*, which in the revolution of that shaft strikes the extended end *o'* of the pawl *h*, tripping such 130 pawl and thereby releasing the bar G and permitting it to be retracted by the spring *g*. The shaft *m* is also provided with a three-pointed cam *p* engaging with the extended end

135

of the spring p' , which plays between two other springs p^2 , p^3 , maintaining its contact with spring p^3 until it touches the spring p^3 , and vice versa.

- 5 The springs p' , p^2 , p^3 form in connection with the three-pointed cam p , a device for operating the answer-back bell L , which is located in the box, and to accomplish this without affecting the main line relay or starting 10 any of the mechanism controlled by such relay, the main line circuit wire 5 passes to the central spring p' , while the main line circuit wire 4 passes to the uppermost spring p^2 , with which the spring p' is normally in contact, thus normally closing the main line circuit through the relay. The lowermost spring p^3 is connected by a wire 16 with a switch N , adapted to be swung upon either of two contacts r , r' . The contact r is connected with 15 a wire 17 running to the outer side of the main line battery, while the contact r' is connected with the wire 4. If the switch N is moved onto the point r' , the movement of the spring p' by the cam p will not produce any effect, since both the springs p^2 and p^3 will then be connected with the wire 4, and the movement of the spring p' , which is connected with the other main circuit wire 5, will be ineffective, since it will close the main line circuit first on one spring and then on the other, keeping it closed on each spring until it touches the other. If, however, the switch N is thrown onto the contact point r , the downward movement of the spring p' will serve to 30 connect the main line wire 5 with the wires 16 and 17 and to open the circuit through the main line wire 4. This will result in closing a local circuit through the main battery and main line relay, which will extend from the 35 inner side of the main battery through the relay, through wire 5, spring p' , spring p^3 , wire 16, switch N , and wire 17, back to the outer side of the main line battery. At the same time, the main line circuit will be opened, allowing the bell L to fall back and make one 40 tap, and this will be accomplished without disturbing the main line relay, which will be kept closed through the local circuit just described. Since the cam p has three points, 45 the effect will be to strike the bell L three times, thus notifying the person at the box that the signal has been received. The shaft m is also provided with a finger q , which strikes the extended end of the spring q' , 50 closing it upon the spring q^2 . The springs q' , q^2 control the circuit to the time-stamp, which circuit is not shown, because it constitutes no 55 part of the present invention.

- It will be understood that the parts n , o , p 60 and q are mounted upon the shaft m at different points in its length, and the four devices upon which these parts act are also similarly located, so that there is no engagement of these parts except with the devices 65 they are intended to affect.

The operation of the emergency bell will be understood from the foregoing description.

In brief, it is as follows:—If the box is pulled with the pointer in the position shown, the first impulse, *i. e.*, that from the notch b , will cause the main line relay to fall back, closing not only the register circuit but also the circuit 10, 11 to the bell-controlling magnet F . This magnet will attract its armature, which through the pawl f will engage the first tooth 70 of the bar G and move such bar forward one step, causing the pawl h to drop into the first notch on the upper side of the bar, holding such bar from retraction and releasing the train K . This train will begin to revolve, and 75 before the spring A' at the signal-box has reached the first notch a , the cam n will strike the spring n' and open the local circuit 10, 11. This cam will remain in contact with the spring n' and keep the circuit 10, 11 open until all the box number notches a have passed beneath the spring A' , when the arm o will strike the beveled end o' of the pawl h , tripping such pawl and releasing the bar G , which bar will be retracted by the spring g to the 90 position shown in the drawing, bringing the tooth on the end of the arm l into the path of movement of the pin on the train and stopping such train. During the revolution of the shaft m , the time-stamp contact springs q' , q^2 95 will be closed by the finger q , and the answer-back springs p' , p^2 , p^3 will be acted on by the three-pointed cam p . This signal from the box will, therefore, be received and be recorded upon the register, and will set in operation the time-stamp and the answer-back springs, but will not move the circuit-controlling bar G a sufficient number of steps to close the circuit to the bell, and hence the bell will not be sounded. The same operation will take 100 place when the box is pulled with the pointer adjusted to either the second or the third report signal, except that the bar G will be moved two notches in one case and three notches in the other. When, however, the 105 pointer is adjusted to the fourth or telephone call, a different operation takes place. The spring A' first sends in an impulse from the notch b , and the spring B' then sends in three impulses from the notches b' , b^2 , b^3 . These 110 four impulses result in the advancement of the bar G four steps, permitting the extended end of the spring i to drop off of the end of the bar G and to close the circuit to the magnet H at the springs i , i' , when the armature 115 k will be attracted and locked in its forward position by the dog k' , closing the circuit to the vibrating bell I , which will continue to ring until the armature k is released by pulling upon the handle k^2 .

The magnet F responds to all of the special signal impulses, but its circuit is opened before the box number impulses are transmitted, as before explained, by the cam n , and after the signal impulses have been received and the bell has been set in motion, the pawl h will be tripped by the arm o and the circuit-controlling bar G will be returned to its initial position, opening the circuit to 130

the magnet H, but this will not affect the circuit to the bell I, which will be maintained closed by the dog k'. The same operation will take place with the fifth and sixth signals, except that a different record will be made upon the register tape.

Since the cam n and the springs n', n² form a circuit-controller, which prevents the operation of the magnet F during the receipt of the box number impulses and permits its operation during the receipt of the special signal impulses, it is evident that by the adjustment of the cam n on the shaft m, that cam could be made to render ineffect-
ive the box number impulses at whatever point in the operation of the transmitting box the box number impulses are brought into action. As, for instance, if the box number preceded the special signal impulses, instead of following them, the cam n would be adjusted so as to normally separate the springs n', n² and keep the circuit 10, 11 open until the box number impulses had been received, when the cam n would leave the spring n' and close the circuit to the magnet F, making such magnet responsive to the following special signal impulses.

What I claim as my invention is—

1. In a police signaling apparatus, the combination with a signal-box, transmitting box number impulses and two or more special service impulses, of a circuit-controller at the central station, having a step-by-step movement and acting to close a bell circuit after making a definite number of such movements, and a device also located at the receiving station for rendering such circuit-controller unresponsive to the box number impulses, whereby a bell will be rung only upon the reception of a definite number of special signal impulses, substantially as set forth.

2. In a police signaling apparatus, the combination with a signal-box adapted to transmit the box number and also to transmit two or more special signal impulses, of a circuit-controller at the receiving station operated by a magnet and having a step-by-step movement, a bell whose circuit is closed only after said circuit-controller has been advanced two or more steps, and another circuit-controller operated by a train and acting to render inoperative the said magnet during the reception of the box number impulses, substantially as set forth.

3. In a police signaling apparatus, the combination with a signal-box adapted to transmit the box number and also two or more

special signal impulses, of a magnet at the receiving station, working a circuit-controller having a step-by-step movement, a bell whose circuit is closed after such circuit-controller has advanced two or more steps, and a circuit-controller operated by a train which is released by said magnet and which acts to open the circuit to said magnet during the reception of the box signal impulses, substantially as set forth.

4. In a police signaling apparatus, the combination with a transmitting box adapted to transmit the box number and one or more special signal impulses, of a magnet at the receiving station, a circuit-controller having a step-by-step movement, operated by said magnet, an alarm bell whose circuit is closed after such circuit-controller has advanced a definite number of steps, a train released by said magnet, a circuit-controller operated by said train and opening the circuit of said magnet during the reception of the box signal impulses, and an arm on said train whose movement trips the step-by-step circuit-controller and allows it to resume its initial position, substantially as set forth.

5. In a police signaling apparatus, the combination with the magnet F and its armature carrying the pawl f, of the sliding bar G having two sets of teeth, the springs i, i' controlling the bell circuit, the spring pawl h, arm l, train K, and tripping arm o, substantially as set forth.

6. In a police signaling apparatus, the combination with an alarm bell at the receiving station, of a relay controlling the circuit of such bell, a spring dog which drops back of the armature of said relay and holds the bell circuit closed, and a hand pull for withdrawing the spring-dog, substantially as set forth.

7. In a police signaling apparatus, the combination with a signal box having an answer-back bell and the main circuit extending from such box to the receiving station, of a motor-train at the receiving station, a magnet in the main circuit controlling said train and releasing the same when affected by a signal upon the main circuit, circuit contacts moved by the train, and an alarm-bell circuit, an answer-back circuit, and a time-stamp circuit controlled by said contacts and acted upon successively, substantially as set forth.

This specification signed and witnessed this 20th day of December, 1892.
